**COMBINED MOTION PICTURE PROJECTOR AND
CARRYING CASE OR SIMILAR ARTICLE**

Robert E. Bourke, Weston, Conn., assignor to
GAF Corporation, New York, N.Y.

Filed Nov. 1, 1971, Ser. No. 194,784

Term of patent 14 years

Int. Cl. D16—02

U.S. Cl. D61—1 K

Fig. 1.

Fig. 2.

Fig. 3.

Fig. 5.

Fig. 4.

Fig. 6.

FIG. 1 is a rear, top and right side perspective view of a combined motion picture projector and carrying case or similar article, showing my new design with the cover on;

FIG. 2 is a right side elevational view thereof with the cover on;

FIG. 3 is a rear elevational view thereof with the cover on;

FIG. 4 is a left side elevational view thereof with the cover removed;

FIG. 5 is a front elevational view thereof with the cover removed; and

FIG. 6 is a rear elevational view thereof with the cover removed.

I claim:

The ornamental design for a combined motion picture projector and carrying case or similar article, substantially as shown and described.
